(57) CLAIM

The ornamental design for a combined portable player and dock for a digital audio player, as shown and described.

DESCRIPTION

FIG. 1 is a perspective view of a combined portable player and dock for a digital audio player illustrating the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side view thereof; and,

FIG. 7 is a left side view thereof.

The broken lines represent the portions of the design that form no part of the claim.
